PRESSURE AND HEAT SEALING UNIT FOR SEALING BAGS OR THE LIKE

Ralph W. Chaffee, San Francisco, Calif.

Application June 16, 1955, Serial No. 36,534

Term of patent 14 years

(Cl. D55—1)

Fig. 1 is a front perspective view of a pressure and heat sealing unit for sealing bags or the like with the casing swung outward and upward showing my new design;

Fig. 2 is a top plan view; and

Fig. 3 is a fragmentary side elevational view of the unit, both sides thereof being the same in appearance and the back of the casing element being substantially plain.

The essential feature of my design resides in the casing member.

I claim:

The ornamental design for a pressure and heat sealing unit for sealing bags or the like, as shown and described.
